Patented Dec. 8, 1914.

UNITED STATES PATENT OFFICE.

CHARLES G. ASHLEY, OF TORONTO, ONTARIO, CANADA, ASSIGNOR TO GENERAL ENGINEERING AND CONSTRUCTION COMPANY, LIMITED, OF TORONTO, ONTARIO, CANADA, A CORPORATION OF ONTARIO.

PERFORATED-TAPE REPRODUCER.

1,120,356.

Specification of Letters Patent. Patented Dec. 8, 1914.

Application filed February 13, 1913. Serial No. 748,157.

To all whom it may concern:

Be it known that I, CHARLES G. ASHLEY, a citizen of the United States of America, and a resident of the city of Toronto, 5 county of York, and Province of Ontario, Canada, have invented a new and useful Improvement in Perforated-Tape Reproducers, of which the following is a specification.

My invention relates to perforating mechanisms and pertains especially to that class 0 of such mechanisms which are electrically controlled and operated and which are utilized especially in the preparation of perforated tapes for printing telegraph sys- 15 tems and the like.

The principal object of my invention comprises producing a device by means of which a transmitting tape, such as is used by well known automatic printing telegraph sys- 20 tems, may be reproduced either locally or at a distance, that such reproduced tape may be used as a transmitting tape in the switching and manual relaying of messages.

One of the chief requirements for the 25 proper operation of a device of this nature is that the operation of tape reproduction be accomplished in substantially the same time interval as that required for the reception of the received printed message, 30 that the transmitting speed need not be lowered when it is desired to produce a reproduction of the transmitting tape. I realize this feature and the above mentioned results by providing a novel system of apparatus and circuits by means of which the 35 weak or relatively weak line impulses are utilized to release locally stored electrical energy of sufficient power to operate the reproduction punch.

40 In the drawing which accompanies and forms a part of this specification, and in which like reference numerals designate corresponding parts, I have illustrated in diagram the apparatus and circuits of my im- 45 proved device in such manner as to clearly bring out the operative relations of the various parts of the same.

In the following description the apparatus 50 controlling the reproduction of tape, or that is the apparatus which reduces the master tape to electrical impulses for the purpose of operating the reproduction apparatus, I will call the transmitter or transmitting apparatus. The reproduction appara-

tus I will designate as the receiver or receiving apparatus, and throughout the specification it should be borne in mind that the act of reproduction may be performed in the same locality as the act of transmission, or it may be performed at any distance from 55 such act of transmission.

In the drawing the transmitting apparatus and its local circuits are shown at the right, while the receiving apparatus and its associated circuits are illustrated at the left, 60 the circuits of the one being connected with the circuits of the other through the conductors 21 and 22 which may or may not be such line conductors as the case may be.

The transmitter 100 comprises an alternating current motor 12 connected through leads 10 and 11 with any source of alternating current. The motor bears loosely 70 sleeved upon its shaft 7 a ratchet wheel 1 and tape drum 3 which are rigidly attached to each other. The ratchet wheel 1 and tape drum 3 are connected to the shaft 7 by a spring 2 and are rotated by the motor 12 and said spring connection, thus the motor 12 is merely a means for winding the spring 75 2 and storing energy therein to rotate the ratchet wheel and drum, consequently the motor 12, as far as driving is concerned, may obviously be operated either by direct or alternating current.

80 Armature 6 is pivoted in a slot through the permanent magnet 8 and is inclosed for a portion of its length by a coil 9 which is connected through leads 10 and 11 to a supply of alternating current. The extremity 85 of the armature 6 which extends above the polarizing magnet 8 bears a pair of detent pawls, the relation of which to the ratchet wheel 1 is such that each vibration of the armature 6 releases the ratchet wheel 1 and 90 allows the tape drum 3 to rotate a distance equal to half of the distance between any two teeth of the ratchet wheel 1. The coil 9, connected to leads 10 and 11, when energized by alternating current causes armature 6 to vibrate in synchronism with the operating alternating current and releases the ratchet wheel 1 to rotate in step with the alternations of the current. The transformer 18 is connected through its primary 100 17 with this same source of alternating current and induces current in its secondary 105 16 which is of the same frequency as the

ratchet operating current. The secondary 16 of the transformer 18 is grounded at one terminal and its other terminal is connected to a platen 13, upon which the line brushes 5 14 and 15 rest with the transmitting or master tape 5 between. The tape drum 3 has a median row of teeth 4 adapted to engage the median row of holes in the tape 5 and thereby impart motion to the tape. 10 Each vibration of the armature 6, as has hitherto been explained, moves the ratchet wheel and tape drum a definite angular distance, and thereby carries the tape 5 through a definite lineal distance which we 15 will hereinafter designate as one transmitting tape unit. The platen 13 is so placed with respect to the axis of the shaft 7 that the contact line of the brushes 14 and 15 with the platen is maintained a distance 20 from the axis of the shaft 7 which is commensurate with the angular rotation of the ratchet wheel 1. Thus the tape 5, when introduced between the brushes and the platen and placed so that its median row of perforations 25 is engaged by the teeth 4 of the drum 3 always allows contact of the brushes 14 and 15 with the platen 13 through the centers of a transverse row of perforations in the tape at instants when the tape drum 30 3 is stationary. Each vibration of the armature 6 moves the tape 5 one transmitting tape unit and brings the center of another transverse row of perforations to coincide with the contact line of the brushes 14 and 35 15 and the platen 13.

Through resistances 19 and 20 a lower voltage alternating current curb is sent to the line conductors 21 and 22 continuously from the secondary 16 of transformer 18, 40 which current serves to operate the receiving tape stepping device as will hereinafter be described, and further in the case where the transmitter and receiver are separated from each other by a relatively great distance, this current serves to maintain an electrostatically clear line, the advantage of which is well known. Thus the transmitter comprises means for impressing on the line conductors at all times an alternating current of definite frequency and relatively low voltage and at predetermined instants depending upon the spacing of the perforations in the transmitting tape, automatically amplifying certain half waves of this 50 constantly applied alternating current and thereby transmitting to the line current impulses of relatively high voltage, which are in phase with the constantly applied alternating current of low voltage.

55 The receiver or tape reproducer comprises a direct current electric motor 48 upon the shaft 49 of which is sleeved frictionally a tape drum 52 and ratchet wheel 50. The tape drum 52 and ratchet wheel 50 55 are rigidly connected together and are ordi-

narily rotated through the shaft 49 by means of the motor 48 when not restrained by double pawl 53. Double pawl 53 is carried by an armature, which is pivoted in a slot through the permanent magnet 55 and is further inclosed for a portion of its length by the coil 54.

A pair of relays 31 and 33 are connected in series and to line conductor 21. Another pair of relays 32 and 34 are likewise connected in series and to line conductor 22, and the relays thus paired are connected together and to one terminal of the coil 54, the other terminal of which is grounded. Relays 31, 32, 33 and 34 are polarized as indicated by the letters near the extremities of their cores. Further, these relays are so wound as to remain unresponsive to the curb current hitherto mentioned, but are wound to respond to the amplified currents transmitted from the secondary of transformer 18 through brushes 14 and 15. An armature as 23, 24, 25 and 26 is maintained opposite each of the relays 31, 32, 33 and 34 respectively and is held against a contact as 35, 37, 39 and 41 respectively by means of springs 27, 28, 29 and 30 respectively. These contacts are all connected together and to the negative terminal of a battery or other source of direct current supply 47 which likewise supplies current for the motor 48 as indicated in the drawing. The armatures 23, 24, 25, 26 are connected to one terminal of the condensers 43, 44, 45 and 46 respectively, the other terminals of which are connected together and to the positive terminal of battery 47. Thus the condensers are all charged to the potential of the battery 47 through the armatures 23, 24, 25, 26 and contacts 35, 39, 37, 41. The contacts 36 and 40 of the polarized relays 23 and 25 are connected together and to one terminal of one of a pair of punch operating magnets as 69, the remaining terminal of which is connected to the conductor joining the terminals of the condensers. The contacts 38 and 42 of polarized relays 32 and 34 are likewise connected together and to one terminal of electromagnet 68 of the pair of punch operating magnets, while the other terminal of this electromagnet is likewise connected to the conductor joining the condenser terminals.

A bell-crank-shaped armature as 62 and 63 is maintained opposite the punch operating magnets 69 and 68 respectively and each of these armatures are normally restrained against a back stop as 66 and 67 respectively by means of the springs 64 and 65 respectively. The short arm of each of the armatures 62 and 63 is pivoted to a punch as 61 and 60 respectively which are held in a guide 58 and are maintained thereby opposite a die 59. A tape 56, provided with a median row of perforations, is carried on a 125 130

tape reel 57 and is drawn between the guide 58 and the die 59 by means of the teeth 51 on the tape drum 52. The spacing of the punches 60 and 61 with respect to each other 5 and the relation of the die 59 is such to the tape 56 that the operation of the punches perforates two longitudinal rows of perforations in the tape, which are spaced a distance from the central row of perforations 10 which corresponds to the spacing of the longitudinal rows of perforations from the median row in the master tape 5.

The operation of the device is as follows: Conceive the motor 12 to be supplied with 15 alternating current, and the motor 48 to be supplied with direct current, and both to be operating to attempt to rotate the ratchet wheels which they bear. Then an alternating current applied to the coil 9 of the 20 transmitter operates armature 6 to release the ratchet wheel 1 to carry tape 5 under the brushes 14 and 15 from left to right as viewed in the drawing, while an alternating current in phase with the ratchet operating 25 current and of low voltage is sent to the line conductors 21 and 22, which traverses but, as hitherto mentioned, does not operate polarized relays 31, 32, 33, 34, and which likewise traverses coil 54 of the receiver stepping 30 device to operate armature 53 to intermittently release ratchet wheel 50 in synchronism with the motion of ratchet wheel 1. Thus operating both ratchet wheel 1 and ratchet wheel 50 in synchronism with 35 the alternations of the curb current. As the currents operating armature 6 of the transmitter and armature 53 of the receiver are of the same frequency, it is obvious that if the tape drums 3 and 52 be of equal diameter 40 the master tape 5 and the receiving tape 56 will be moved through equal lineal distances in the same time intervals. As the tape 5 is drawn through the transmitter, contact is made by either brush 14 or 15 45 with the platen 13 as the case may be, which allows an amplified half current wave of the curb current to traverse line conductors 21 and 22 as the case may be dependent upon which of the brushes 14 or 15 are making 50 contact with platen 13. This amplified current traverses a pair of the polarized relays and one or the other of the pair of relays, depending upon the direction of the current flow, will be energized to induce in its core 55 magnetism which will build up the polarizing magnetism therein to a value which will cause the armatures associated with that relay to operate to disconnect the condenser associated with that armature from the battery 47 and to connect this condenser in series with one or the other of the punch operating electromagnets as 69 and 68 to thus 60 discharge the condenser through the coil of this electromagnet to operate its associated armature and perforate the tape 56. Thus

the perforations in the tape 5 are reproduced in the receiving tape 56, as punch 61 operates to reproduce the perforations in the master tape 5 through which brush 14 makes contact with platen 13, while punch 70 60 operates to reproduce the perforations in the master tape through which brush 15 makes contact with the platen. And as the amplified currents which operate the tape perforator are in phase with the ratchet 75 wheel operating currents, it follows that the reproduced perforations will be spaced as the perforations in the master tape.

In the specified embodiment of my device herein disclosed I have illustrated but two 80 punches adapted to reproduce the master tape, which comprises two longitudinal rows of operating perforations, but it is obvious that more line brushes may be provided on the transmitter and that the apparatus of 85 the receiver may be duplicated to accomplish the reproduction of a master tape of any number of longitudinal rows of perforations.

Having thus described my invention, 90 which I claim as new and desire to secure by United States Letters Patent, is as follows:—

1. In a perforated tape reproducer, a master tape, means for reducing perforations 95 therein to electrical current impulses, a source of current, condensive means for storing same, a record tape, means associated therewith for perforating the same and means for utilizing said electrical current 100 impulses to release energy from said storage means to operate said perforating means to perforate said record tape.

2. In a perforated tape reproducer, a first set of electromagnets, a second set of electromagnets, a plurality of tape punches operated by said second set of electromagnets, means for operating said first set of electromagnets to release condensively stored electrical energy to energize selectively the magnets 105 of said second set of electromagnets to operate said tape punches selectively.

3. In a perforated tape reproducer, a transmission line, means for energizing said line with current impulses in predetermined 115 code, means for receiving said impulses, a plurality of electromagnets, a plurality of tape punches operated thereby and means for utilizing said current impulses to release condensively stored electrical energy to energize said electromagnets selectively to operate said tape punches.

4. In a perforated tape reproducer, a transmission line, a pair of relays associated with each conductor of said line, a condenser 125 associated with each of said relays, a pair of electromagnets, a tape punch associated with each of said magnets, a source of current with which said condensers are normally connected, and means for transmitting over 130

said transmission line current impulses to energize said relays selectively to disconnect any one of said condensers from said source of current and discharge said condensers 5 through one of said pair of electromagnets to operate the tape punch which it controls.

5. In a perforated tape reproducer, a master tape, a record tape, means for imparting intermittent motion to said master tape, 10 means associated with said master tape moving means to move said record tape in synchronism with said master tape, means for transforming the perforations in said master tape to current impulses and means for 15 utilizing said current impulses to perforate said record tape.

6. In a perforated tape reproducer, a master tape, a record tape, means for imparting intermittent motion to said master tape, 20 means associated with said master tape moving means to move said record tape in synchronism with said master tape, means for transforming the perforations in said master tape to current impulses, a source of current supply, 25 and means for utilizing said current im-

pulses to release current from said storing means to perforate said record tape.

7. In a perforated tape reproducer, a master tape, a record tape, means for imparting 30 intermittent motion to said master tape, means associated with said master tape moving means to move said record tape in synchronism with said master tape, means for transforming the perforations in said master tape to current impulses, a plurality of electromagnets, a plurality of tape punches operated thereby, a source of current supply, means for storing the same and means for utilizing said current impulses to release 35 current from said storing means to energize selectively said electromagnets to operate said tape punches selectively to perforate said record tape.

Signed by me at Toronto, county of York 45 and Province of Ontario, Canada, in the presence of two witnesses.
